UNITED STATES PATENT OFFICE.

CLARA HERMINA BORGESON HOLMES AND OSCAR GOTTHARD HOLMES, OF CLEVELAND,
OHIO.

TESTING DEVICE FOR IGNITION SYSTEMS.

1,290,995.

Specification of Letters Patent.

Patented Jan. 14, 1919.

Application filed January 21, 1918. Serial No. 213,020.

To all whom it may concern:

Be it known that we, CLARA H. B. HOLMES and OSCAR G. HOLMES, citizens of the United States, and residents of Cleveland, 5 in the county of Cuyahoga and State of Ohio, have invented certain new and useful Improvements in Testing Devices for Ignition Systems, of which the following is a specification.

10 Our present invention relates to a testing device for ignition systems, and more particularly to a device of this character with which tests can be made to determine the efficiency of generating mechanism or of 15 spark plugs when subjected to substantially the same conditions as are encountered when the parts are installed as the ignition system for an internal combustion engine.

It has been found in testing magneto and 20 battery ignition systems that they will often show what seems to be a good spark when tried in the open, but will not fire and act efficiently when under compression charge. Therefore, it is the principal purpose of our 25 invention to provide a test device or system which can be used to test spark plugs as installed in an ignition circuit with the spark plug fitted to a closed container in which any desired pressure can be obtained, 30 and which closed container is of such construction that the action of the spark plug can be watched.

A further object resides in so constructing the device that it can be applied to test a 35 system including one or more spark plugs, and can be connected in circuit wiring already installed for the ignition system.

Another object resides in providing means by which any desired pressure can be attained 40 in the chambers to which the spark plugs are fitted, and in associating with the same pressure indicating means to thus permit accurate gaging of the pressure under which the system is tested.

45 Further objects of our invention will appear in the following detailed description, taken in connection with the accompanying drawings, forming a part of this specification, and in which drawings:

50 Figure 1 is a view in elevation of a device constructed after the manner of our invention and with circuit connections diagrammatically illustrated.

55 Fig. 2 is a transverse vertical sectional view taken on the line 2—2 of Fig. 1.

Fig. 3 is a fragmentary sectional view illustrating the fitting of a bushing to adapt the device for use with spark plugs of different sizes.

In the drawings, where similar characters 60 refer to similar parts throughout the views, A designates a base member which is of metal, and B is a top member, also of metal. The base and top members A and B are made as strips of suitable length and are 65 adapted to be mounted in parallel disposition as shown in Fig. 1. A plurality of tubular members C, which are of glass or other suitable transparent material are mounted between the base and top members 70 A and B and these members are drawn down against the ends of the tubular members C by the clamp bolts D. A pressure pump E, which can be of the hand or mechanically operated type, has a compressed air supply 75 pipe F leading therefrom and extending substantially parallel with the top member B, and branch air supply pipes G are led from this pipe F to extend through the top member B and open within each of the 80 tubular members C, a pressure gage H being also connected with the interior of one of the tubular members so that the pressure of fluid through operation of the pump E is at all times determinable. In Fig. 1 of 85 the drawings, we have illustrated the device of our invention connected in an ignition system such as would ordinarily be used for an internal combustion engine, and as is shown the system includes a generator I, 90 a breaker J, and a distributor K, with suitable circuit wiring.

As has been stated, the tubular members C are fitted between the base and top members, and to insure that the tubular members 95 will be maintained in the proper positions at all times, the base member A is counter-bored, as indicated at 1, while the top member B is correspondingly counter-bored as at 2, it being understood that the recesses 100 thus formed are so proportioned that the tubular members C will substantially fit and fill out the same when their ends are plated therein. To establish a fluid tight connection between the tubular members C and the base 105 and top members, and thus provide a closed compartment within each of the tubular members, the packing rings 3 and 4 are mounted in the counter-bored recesses of the base and top members to have the ends of 110

the tubular members C bear thereagainst, and then as the clamp nuts 3 are tightened upon the clamp bolts D, the base and top members A and B are properly clamped 5 against the ends of the tubular members C and the entire structure thus assembled includes a plurality of air tight compartments with transparent walls, the branch pipes G extending from the compression air supply 10 pipe F establishing a direct communication from the pump E.

As the spark plugs fitted in the ignition system which is to be tested, are to be so fitted that the spark gaps will be within 15 the air tight compartment, the top member B has a plurality of screw-threaded openings 6 provided therethrough and so spaced that each of these openings is substantially centered within one of the tubular members 20 C, and thus a spark plug, as indicated at L, can be fitted to have the sparking terminals thereof within the air tight compartment, and at the same time these sparking terminals will be clearly visible through the 25 transparent member C. As the device may be used to test systems including spark plugs of different sizes, it is preferably that the screw-threaded openings 6 be made to take a spark plug of maximum size, and that 30 bushings M, as shown in Fig. 3, be provided to adapt the device for use with spark plugs of smaller sizes. One or more sets of the bushings M might be provided, and it will of course be appreciated that the screw- 35 threaded central bore 7 will be made of a size and threaded in a manner to receive smaller spark plugs than might fit within the opening 6 of the top member B. That the bushings may be readily fitted in place 40 and removed, the polygonal head portions 8 are provided, and it will of course be understood that where necessary or desirable, packing washers 9 might be employed to insure an absolutely tight connection of each 45 bushing. This position of the bushings adapts the device for use where spark plugs are of large or small size, and as it is preferably that some six or more of the transparent members C be mounted between the 50 base and top bars A and B, to thus adapt the device for use upon the ignition system of an engine having a number of cylinders, it will also be understood that provision must be made for cutting out or disconnecting cer- 55 tain of the branch pipes G from the compressed air supply pipe F when the compartments to which they lead are not in use, as otherwise air supplied through these pipes would escape through the openings 6 60 and in consequence, it would not be possible to obtain the desired fluid pressure within the chambers to which active spark plugs are fitted. With this in mind, the cut off valves 10, 11, 12, 13 and 14, are connected in cer- 65 tain of the branch pipes G. In this connec-

tion it is preferably that no valve be fitted to the pipe connecting with the compression chamber having the gage H associated therewith, as to properly determine the fluid pressure within any one of the tubular members 70 C, it is essential that a corresponding pressure be generated within the compression chamber with which the gage H is connected.

It will of course be appreciated that the 75 use of the device will be the same whether it be installed to test a single spark plug or to test a system including a maximum number of spark plugs for which the device is constructed, and in the present illustration, 80 we have shown the connection which is established in testing the spark plugs and the ignition system of a four cylinder engine. As six compression chambers are embraced within the device as here illustrated, the 85 valves 13 and 14 are closed so that communication is established and maintained from the compression air supply pipe F to but four of the compression chambers, and then the spark plugs 15, 16, 17 and 18, are fitted to 90 and set within the threaded openings 6 which open into those compression chambers still connected with the compressed air supply pipe. The usual circuit connections from the distributor to the spark plugs are 95 maintained, and a part of the frame structure including the base and top members is grounded on the engine structure or the ground wire from the generator is connected therewith. When this connection 100 has been established, the pump E is operated to obtain any desired fluid pressure within the compression chambers to which the spark plugs are fitted, which pressure will be indicated by the gage H, and then by reason 105 of the fact that the tubular members C are of a transparent material, the action of the spark plugs under any given pressure or under varying pressures can be accurately determined. As under some circumstances, 110 it may be desired to reduce the pressure and observe the action under these conditions, and again the pressure must be partially reduced before the spark plugs are removed, an outlet valve 19, which might well be of 115 the three-way type is connected in the pipe F where the same leads from the pump E. It will of course be understood that when the pressure is being raised in the compression chambers, this valve 19 will be set to establish 120 a straight passage through the pipe F and that the pipe will be substantially continuous, but when the pressure is to be reduced, the valve is set to establish communication from the several branch pipes 125 through the connected length of the pipe F and then through the exhaust opening 20 of the valve.

While we have herein described the device 130 as particularly adapted for use in testing

spark plugs and an ignition system to determine the effect of varying pressures at the spark terminals, it will of course be appreciated that the device will at the same time, give the user an opportunity to determine the relative intensity of the spark of the several spark plugs, to accurately adjust the width of the spark gap and then observe the effect of such adjustment, and to determine whether the circuit connections are properly made to secure sequential firing in the use of the engine with which the ignition system is installed.

Changes in details may be made without departing from the spirit or scope of our invention; but

We claim:

1. A spark plug and ignition tester including base and top members made in the form of elongated bars adapted to be mounted in parallel relation, said base and top members being provided with counter-bore openings on adjacent faces thereof, tubular members of transparent material fitted between said base and top members with their ends in the counter-bores of said members, clamp bolts by which the base and top members are tightened against the tubular members to form fluid tight compression chambers, said top member having openings therethrough for the reception of spark plugs to dispose the sparking terminals of said plugs within the compression chambers, a compressed air supply pipe, branch pipes extending from the air supply pipe to each of the several compression chambers, cut off valves connected in several of said branch pipes, a pressure gage connected with one of the compression chambers, a pump by which air is supplied to the main pipe, and

a valve connected in said pipe to reduce and relieve the fluid pressure within the chambers.

2. A spark and ignition tester including a pair of rectangular metal plates, a plurality of transparent cylinders supported between said plates, and in fluid tight connection therewith, the uppermost of said plates provided with openings adapted to receive a spark plug with the sparking terminals within the transparent cylinders, a pipe for supplying air under pressure having a plurality of branch pipes entering said transparent cylinders through said top plate, and means whereby the inlet or exhaust of fluid under pressure into or from said transparent cylinders independently of each other or in unison may be accomplished.

3. A spark plug and ignition tester including a pair of rectangular parallel metal plates provided with counter bores in their facing surfaces, transparent cylinders having their ends fitting in said counter bores, packing washers between the ends of the cylinders and the plates for forming a fluid tight joint between the cylinders and plates, one of said plates provided with openings adapted to receive spark plugs with the sparking terminals within the chambers of the transparent cylinders, a pipe for supplying fluid under pressure, branch pipes carried by said first pipe and extending into said cylinders, and means for controlling the inlet into or exhaust of fluid under pressure to or from said cylinders whereby any one of the cylinders may be charged or relieved independently of the others.

CLARA HERMINA BORGESON HOLMES.
OSCAR GOTTHARD HOLMES.
